Primary Examiner — Selina Sikder*(74) Attorney, Agent, or Firm* — Banner & Witcoff, Ltd.(57) **CLAIM**

The ornamental design for a light-emitting diode, as shown and described.

DESCRIPTION

FIG. 1 is a front perspective view of a light-emitting diode, showing our new design;

FIG. 2 is a rear perspective view thereof;

FIG. 3 is a front elevational view thereof;

FIG. 4 is a rear elevational view thereof;

FIG. 5 is a top plan view thereof; the opposite side being a mirror image thereof;

FIG. 6 is a right side elevational view thereof; the opposite side being a mirror image thereof; and,

FIG. 7 is an end view thereof, taken along the line 7-7 in FIG. 3, with its internal mechanisms omitted.

The broken lines are for illustrative purposes only and form no part of the claimed design.
